SAFETY CLOSURE FASTENER FOR
WINDOWS AND DOORS

Robert H. Hummert and George E. Gravenstine,
Dayton, Ohio, assignors to The S. H. Thomson
Manufacturing Company, Dayton, Ohio, a cor-
poration of Ohio

Application July 9, 1932. Serial No. 621,642

2 Claims. (Cl. 292—78)

This invention relates to new and useful im-
provements in safety closures for windows and
doors.

It is one of the principal objects of our inven-
tion to provide for attachment to windows and
doors, and particularly those of the underscreened
operated type, a safety closure that will auto-
matically close tightly one or more hinged sash
without exposing the closure member to acci-
dental operation that would defeat the purpose
for which it was designed. For instance, closure
members at present in use are open to the ob-
jection that a window washer or someone else
may, by unintentionally contacting the device,
cause it to assume a position to prevent the clos-
ing of the window.

Our simple and efficient closure latch unit, on
the other hand, embodies a closure cam which
cannot be forced over center until it is unlocked
by a release member which must first be raised
by the front wall of the channeled sash head be-
fore it can be pushed beyond center by the rear
wall of that head. Similarly, one cannot, by
accidentally brushing against the cam locking
arm unit, spring it over center unless the release
member is first raised. This is unlikely, since,
for instance, it would have to be raised by one
hand and the cam arm forced over center by the
other.

Our safety closure is equally applicable to a
single or dual window sash to tightly secure
either to the screened window frame.

Other important and incidental objects will be
brought out in the following specification and
particularly set forth in the subjoined claims.

In the accompanying drawing illustrating our
invention, Figure 1 is a front view of a screened
window casing or frame containing two ver-
tically hinged window sash. Figure 2 is a sec-
tional view taken through the head of the window
frame and our attached safety closure just be-
fore the latter is engaged by a swinging window
sash. Figure 3 is a sectional view taken through
the same, showing how the hinged window sash
is held in a closed position by the closure member.
And Figure 4 is a front view of our safety closure
member.

Referring to the accompanying drawing for
a detailed description of our invention, the nu-
meral 1 designates a window frame or casing
preferably constructed of metal and fitted with
a stationary screen 2. Beyond the screen two
companion window sash 3 and 4 are vertically
hinged to the window frame, for operation
55 through fly-tight openings in it by right and left

underscreen operators 5 and 6 mounted on the
window ledge 7 and of the type covered by United
States Letters Patent No. 1,860,418, granted May
31st, 1932 to Robert H. Hummert.

For the purpose of firmly holding the single or 60
dual window sash in a closed position, we have
provided a safety closure now to be described.
This closure is not only simple in construction
and automatic in operation, but it is proof against
accidental operation by a servant or window 65
cleaner to bring its closure cam to a position
where it would block the closing of the window.

Our safety closure unit comprises a casting 8
having a flat, horizontal top 9 formed with screw
holes by which it may be attached to the under 70
side of the channel head 10 of the window frame
1 by screws 11, and a plate 12 resting upon said
head for engagement by the heads of the screws.

The casting 8 has two downwardly projecting
side ears 13 and 13^a between which there is an 75
integral apron portion 14 that inclines down-
wardly to a substantially rounded lower end 15.

Pivoted to the inner portions of the lower ends
of the ears 13 and 13^a on the casting 8, by pivot
pins 16 are curved cam arms 17 and 18 respec- 80
tively. At their rear ends these arms are con-
nected by a stub shaft 19 on the reduced end
portions of which rollers 20, 20 are rotatably
mounted. Secured to the shaft 19 between the
rollers 20, 20 is the hook end 21 of a helical 85
spring 22, its other end being hooked into an
aperture 23 in an ear 24 projecting downwardly
from the top inner surface of the casting behind
the vertical plane of the pivot pins 16.

The connected cam arms 17 and 18 are so se- 90
cured to the casting 8 that when their roller ends
are engaged by the rear wall 25 of the channel
portion 26 of the head of the window sash 4,
they will be drawn over center by the spring 22.
During this violent forward movement effected 95
by the spring, the roller ends of the cam arms
will engage the short front wall 27 of the chan-
neled head of the window sash to force the lat-
ter to a tightly closed position against the other
sash 3 which is closed ahead of it. Thus both 100
sashes are tightly held against the screened win-
dow frame 1 by our single safety closure unit.

In order that the closure cam unit just de-
scribed may not be accidentally forced over cen-
ter by a servant or other person, to a position to 105
block the closing of the window, we have provided
the following safety means which must first be
actuated to release the closure cams.

Referring to Figures 2, 3 and 4, there is pivot-
ally secured to the outer face of the ear 13^a on the 110

casting 8, by a screw 28, the upper end of a release foot-shaped member 29. Projecting inwardly from the heel part of the member 29 is a lock pin 30 which, when the release member is 5 in its normal position as shown in Figure 2, engages in a curved recess 31 in the inner end of the cam arm 18. The release member 29 is held in this position by a helical spring 32 connected between a pin 33 on it and a pin 34 on the fixed 10 ear 13^a. When and until the release member is moved upwardly by some independent force, to raise the lock pin 30 clear of the recessed end of the cam arm 18, the latter and its companion arm 17 cannot be thrown over center. This practically insures against accidental snapping of the 15 cam arm unit over center by the hand or arm of a window washer for instance, for the release member must be held up by the other hand to permit such an unintended actuation of the cam arm unit.

20 Since the release arm 29 must first be raised to permit the window sash to throw the cam arm unit over center to effect a tight closing of the window, we have provided the following means for attaining this end. Pivotedly secured at its upper end by a large headed pin 35 to the toe end of the release member 29 is a pawl 36 which is pointed at its lower end, and notched at its upper end to form a shoulder 37. The clockwise movement 25 of this pawl is limited through the engagement of this shoulder 37 with a pin 38 on the toe end of the release member, so that if the pointed lower end of the pawl is engaged by an object moving to the left, it will raise the release member above the recessed end of the cam arm 18 against the 30 tension of the spring 32.

35 This is just what occurs when the window sash 4 moves inwardly, since the pointed end of the pawl 36 is in the path of inward movement of the front wall 27 of the channeled head of the sash. 40 When this wall engages the pawl as shown in Figure 2, it will raise the release member 29 clear of the recessed end of the cam arm 18, so that the latter and its companion arm 17, when engaged by the rear wall 25 of the channeled sash 45 head, will be thrown over center to permit the

spring 22 to draw the cam unit against the front wall 27 with sufficient force to close the sash 4, and the sash 3 ahead of it, tightly against the screened window frame. (See Figure 3.)

When the window sash 3 and 4 are again 80 opened, the sash 4 will force the cam unit rearwardly over center to the position it occupies in Figure 2, the spring 32 thereupon drawing the release arm 29 to its locking position over the recessed end of the cam arm 18 to prevent its accidental operation to a closure blocking position while the window is open.

85 Having described our invention, we claim:

1. A fastener for securing a hinged structure 90 within a frame, comprising a closure bracket attachable to said frame, a cam pivotally secured in said bracket, a spring secured between the bracket and the outer end of the cam to throw it over center, whereby it will engage and force the structure tightly against the frame, and pawl means pivotally secured to the bracket to lock the cam against inward movement until said pawl means is first actuated by the inwardly moving structure to unlock the cam.

2. A fastener for securing a hinged structure 100 within a frame, comprising a closure bracket attachable to said frame, a cam pivotally secured in said bracket, a spring secured between the bracket and the outer end of the cam to throw it over center, whereby it will engage and force the structure tightly against the frame, a locking arm pivotally secured at its upper end to the bracket, a projection on said arm to engage the inner end of the cam to prevent its upward movement, a spring connected between the lower end of 110 the arm and the bracket, a pin on the lower end of said arm, and a pawl pivoted to the latter for engagement by the inwardly moving sash, whereby said pawl will engage the pin and raise the arm above locking engagement with the cam, to 115 permit the cam to be sprung over center by the spring after it is engaged by the structure, for the purpose specified.

120 ROBERT H. HUMMERT.
